UNITED STATES PATENT OFFICE.

ISAAC HUDSON SAPP, OF CHEYENNE, WYOMING.

DRUM-SNARE.

1,227,496.

Specification of Letters Patent.

Patented May 22, 1917.

Application filed July 21, 1913, Serial No. 780,352. Renewed October 25, 1916. Serial No. 127,688.

To all whom it may concern:

Be it known that I, ISAAC HUDSON SAPP, a citizen of the United States, residing at Cheyenne, in the county of Laramie and 5 State of Wyoming, have invented a new and useful Drum-Snare, of which the following is a specification.

The present invention relates to improvements in drum snares, one object of the invention being the provision of means whereby the usual form of snare made of a non-sonorous material is supported at its respective ends by reduced terminals so as to be non-sonorous, such support constituting a 15 means whereby the snare is vibrated much easier than the usual snare thus producing a more sensitive and brilliantly toned drum.

A still further object of the present invention is a snare in which the amount of 20 snare material is greatly reduced, due to the reduced supporting and tightening connections at the ends thereof.

With the foregoing and other objects in view which will appear as the description 25 proceeds, the invention resides in the combination and arrangement of parts and in the details of construction hereinafter described and claimed, it being understood that changes in the precise embodiment of 30 the invention herein disclosed can be made within the scope of what is claimed without departing from the spirit of the invention.

In the drawings—

Figure 1 is a top plan view of a snare 35 drum with the present invention applied thereto.

Fig. 2 is a side elevation of the snare hoop with the snare carrying casings attached thereto, a portion of the hoop being shown 40 in section to illustrate the position of the snares within.

Fig. 3 is an enlarged detail view of a single snare *per se*.

Figs. 4 and 5 are detailed sections and 45 side elevations of the present snare connected to the common form of support.

Referring to the drawings, the numeral 1 designates the snare hoop, having adjustably attached at diametrically opposite sides 50 thereof two exteriorly projecting casings 2 and 3 respectively. The casing 3 is provided with the transversely disposed spindle 4 which is rotated through the medium of the worm gears 5 and 6. Connected to the 55 spindle 4 within the casing 3 are the reduced terminals 7 of the snares 8. The terminals

7 and 9 of the snares 8, as clearly illustrated in Fig. 3, are attached to the respective ends of the snare 8 and constitute a "hair" support for the snare, and thus 60 permit of the closer positioning of the snares, relative to each other, and at the same time by reducing the supporting ends thereof as relates to the spindle 4 and the casing 2 permits the more rapid and easy 65 vibration of the snare body 8 and consequently imparts a better tone to the drum. Furthermore, by utilizing the reduced terminals 7, they can be more abruptly bent back over the marginal portion of the drum 70 head than would be possible should a snare of ordinary construction be employed. Consequently the snare can be placed under greater tension and thus rendered more sensitive. The terminals 9 in order that the 75 respective snares may be adjusted individually and independently, have attached to their extreme ends, the screws 10 which are threaded into the outer wall of the casing 2 and are operated by means of a screw driver, 80 to increase or decrease the tension upon the respective snares, while the connection of the terminals 7 to the spindle 4 is such, that all of the terminals may be wound thereupon by the actuation of the worm 6. 85

The body 8 of the snare is preferably formed of gut while the terminals 7 and 9 are composed of cord, wire, or in fact any supporting material that can be properly connected to the ends of the snare body and 90 impart the necessary tautness thereto when in the position as shown in Figs. 1 and 2.

In the present instance, the supporting connections 7—9 are threaded through the respective ends of the snare body 8 and tied 95 thereto.

It is also apparent that these terminals 7 and 9 may be formed by reducing the ends of the snare body 8 in any desired manner, by cutting or scraping as may be found desirable. 100

It is desirable in constructing the present snare, that the terminals 7 and 9 be of a more flexible material and be smaller in diameter than the body of the snare and as before 105 stated, the same may be composed of a portion of the body of the snare or be composed of wire or cord. In the preferred construction, the snare body 8 is composed of gut, while the terminals 7 and 9 are gut or cord 110 of lesser diameter than the body 8.

As shown in Figs. 4 and 5, the snare body

8 with its terminals 7 and 9 are connected to the usual fastenings 11 and 12 of an ordinary drum 13, the main body of the snare being so disposed that the reduced terminals 7 and 9 extend from a point slightly within the casing of the drum to the fastening devices 11 and 12.

Thus it is apparent that the present form of snare may be readily attached to a snare hoop as shown in Figs. 1 and 2 or to the ordinary snare drum, as illustrated in Figs. 4 and 5.

What is claimed is:

1. A drum head, and a snare having reduced terminals bent back over the marginal portion of the head and holding the snare in contacting relation with the head, and attaching means engaging the terminals of the snare.

2. The combination with a drum, opposed snare fastening means thereon, and a drum head, of a snare having reduced terminals bent abruptly over the margin of the head and engaged by the fastening means.

3. The combination with a drum head and 25 opposed fastening devices adjacent the head, of a snare extending across the head and having reduced terminal portions connected to the fastening devices for holding the snare in contacting relation with the head. 30

In testimony that I claim the foregoing as my own, I have hereto affixed my signature in the presence of two witnesses.

ISAAC HUDSON SAPP.
